United States Patent [19]

Guldalian, Jr.

[11] Patent Number: Des. 299,746

[45] Date of Patent: ** Feb. 7, 1989

[54] INSTRUMENT FOR MEASURING NERVE CONDUCTION VELOCITIES

4,157,087 6/1979 Miller et al. .... 128/422 X
4,697,599 10/1987 Woodley et al. 128/734

[75] Inventor: Jack Guldalian, Jr., Lawrenceville, N.J.

Primary Examiner—Wallace R. Burke

Assistant Examiner—Stella M. Reid

Attorney, Agent, or Firm—James C. Nemmers

[73] Assignee: Neurotron, Inc., Lawrenceville, N.J.

[57] CLAIM

[**] Term: 14 Years

The ornamental design for an instrument for measuring nerve conduction velocities, as shown.

[21] Appl. No.: 856,134

DESCRIPTION

[22] Filed: Aug. 21, 1986

FIG. 1 is a front elevational view of an instrument for measuring nerve conduction velocities showing my new design;

[52] U.S. Cl. D24/17

FIG. 2 is a left side elevational view thereof;

[58] Field of Search D24/17, 40, 41;
128/741, 734, 744

FIG. 3 is a right side elevational view thereof;

D24/17 X

FIG. 4 is a rear elevational view thereof;

D. 290,095 6/1987 Montalbano et al. .... D24/17 X
4,064,870 12/1977 Dumitrescu et al. 128/741

FIG. 5 is a top plan view thereof; and

FIG. 6 is a bottom plan view thereof.
